FIG. 2

FIG. 3.

FIG. 4.

INVENTOR
JACOB PODOLSKY
BY *David Rudes*
ATTORNEY

UNITED STATES PATENT OFFICE

JACOB PODOLSKY, OF DORCHESTER, MASSACHUSETTS

VALVE

Application filed October 17, 1931. Serial No. 569,406.

The present invention relates to valve constructions, and more particularly to supports for float valves.

Supports of the above-described character commonly comprise a valve-stem that supports a bracket comprising a split-ring mounted about an overflow pipe made of rolled metal, such as brass, the split ends of the ring being secured together by a screw. There are three chief objections, among others, to this construction. In the first place, the screw loosens, rendering the device wobbly; secondly, the screw has a constricting tendency against the overflow tube; and thirdly, the rolled metal corrodes rapidly, in use, to overcome these difficulties, and in realization of the fact that cast metal does not corrode so readily, the overflow pipe and the bracket have been cast in one piece, but this one-piece structure has certain disadvantages. Other solutions of the problem have also been proposed, among them the substitution of the more expensive copper for brass.

It is an object of the present invention to improve upon valve construction of the above-described character. Other and further objects will be explained hereinafter.

With the above ends in view, a feature of the invention resides in casting the overflow pipe integral with a collar for supporting a separate valve-stem-supporting bracket. The collar may have a supporting portion and an enclosing wall for supporting and confining a ring integral with the bracket, the ring being held securely in place by a set screw threaded through the enclosing wall into engagement with the ring.

The invention will now be explained in connection with the accompanying drawing, in which Fig. 1 is an elevation, partly in section, of a valve construction of the above-described character, illustrating a preferred embodiment of the present invention, the section being taken upon the line 1-1 of

Fig. 2, looking in the direction of the arrows; Fig. 2 is a section taken upon the line 2-2 of Fig. 1, looking in the direction of the arrows, the section of Fig. 2 being upon a larger scale; Fig. 3 is an elevation illustrating the invention; Fig. 4 is a perspective showing the parts detached; and Fig. 5 is a section taken upon the line 5-5 of Fig. 1, looking in the direction of the arrows.

The overflow pipe 2 is made of cast metal, such as bronze, integral with a collar 4, and is provided with a valve seat 6 which may be joined thereto at 7. The collar 4 is provided with a supporting portion 8 and an enclosing wall 10, the wall being cut away at 12 on the side next to the valve seat. The collar 4 is provided with a second enclosing wall 14 parallel to, and concentric with, the enclosing wall 10, so that a circular groove 16 is formed between the enclosing walls 10 and 14. As the walls 10 and 14 are integral with the collar 4, a cast bronze structure is thus provided all in one piece having the groove 16 for receiving a continuous ring 18 that is cast in one piece with an arm 20 and valve-stem guide 22. The parts 18, 20 and 22 thus constitute a bracket separate from the collar 4.

The arm 20 is provided with a lug 24 at its junction with the ring 18 and has side walls 26, 28 that engage against the cut-away sides 12 of the enclosing wall 10. The lower portion 30 of the lug 24 engages against a shoulder 32 that is cut away in the supporting portion 8 of the collar 4. The bottom wall 34 of the ring 18 is thus supported on the supporting portion 8 and is enclosed between the walls 10 and 14, the bottom 30 of the lug 24 engaging snugly against the shoulder 32, and the walls 26 and 28 contacting snugly against the sides 12 of the enclosing wall 10. In this way, the parts are rigidly held together without possibility of accidental side play.

The pipe 36 is provided at its lower end

with threads 38 that are screwed into threads 40 on the inner side of the wall 14. Not only that, but they are threaded also into corresponding threads 42 on the inner wall 5 of the ring 18. In this manner, the parts 2 and 36 are joined together as a unit and, at the same time, they are made rigid with the collar 18. By reason of this construction, therefore, the valve-stem guide 22, in 10 which the valve stem 44 is guided, is held rigidly in place.

To take up possibilities of residual side play, however, such as might occur after periods of use, a universal joint is provided 15 at 46 between the valve stem 44 and the valve 48 seated on the valve seat 6.

The customary set screw (not shown) may be employed extending through the wall 10 into engagement with the ring 18, but it is 20 found in practice that such set screw is not needed.

Modifications will occur to persons skilled in the art and all such are considered to fall 25 within the spirit and scope of the invention as defined in the appended claims.

What is claimed is:

1. A valve construction comprising an 30 overflow pipe having a collar integral therewith and provided with a valve seat, the collar having a supporting portion and an enclosing wall, a bracket having a ring and a valve-stem guide, the ring being mounted about the pipe and being supported on the supporting portion and enclosed by the enclosing wall, a valve stem guided in the guide, and a valve adapted to be seated on the valve seat and connected with the valve stem.

2. A valve construction comprising an 40 overflow pipe having a collar integral therewith and provided with a valve seat, the collar having a supporting portion and an enclosing wall, the wall being cut away on the side next to the valve seat, a bracket having 45 an integral, one-piece, continuous ring, a valve-stem guide and an arm connecting the ring and the guide, the ring being mounted about the pipe and being supported on the supporting portion and enclosed by the enclosing wall, the arm extending through the cut-away side of the wall, a valve stem guided in the guide, and a valve adapted to be seated on the valve seat and connected 50 with the valve stem.

3. A valve construction comprising a cast- 60 metal overflow pipe having a collar integrally cast therewith and provided with a valve seat, the collar having a supporting portion and an enclosing wall, a bracket having a ring and a valve-stem guide, the ring being mounted about the pipe and being supported on the supporting portion and enclosed by the enclosing wall, a valve stem 65 guided in the guide, and a valve adapted to

be seated on the valve seat and connected with the valve stem.

4. A valve construction comprising an 70 overflow pipe having a collar integral therewith and provided with a valve seat, the collar having a supporting portion and two enclosing walls forming a groove between them, a bracket having a ring in a valve-stem guide, the ring being supported on the supporting portion in the groove, a valve stem guided in the guide, and a valve adapted to be seated on the valve seat and connected with the valve stem.

5. A valve construction comprising an 80 overflow pipe having an interiorly threaded collar integral therewith and provided with a valve seat, a pipe having a threaded portion engaging with the threads of the collar, a bracket having an interiorly threaded ring threaded upon the threads of the second-named pipe, a valve stem guided in the bracket, and a valve adapted to be seated on the valve seat and connected with the valve stem.

6. A valve construction comprising an 90 overflow pipe having a collar integral therewith and provided with a valve seat, the collar having a supporting portion and two enclosing walls forming a groove between them, the inner wall being interiorly threaded and the outer wall being cut away on the side next to the valve seat, a bracket having 95 an integral, one-piece, continuous ring, a valve-stem guide, and an arm connecting the ring and the guide, the ring being mounted in the groove and being interiorly threaded, a pipe having threads engaging with the threads of the collar and the ring, the arm of the bracket extending through the cut-away side of the wall and engaging snugly 100 against the said cut-away sides, a valve stem guided in the guide, and a valve adapted to be seated on the valve seat and connected with the valve stem.

7. A valve construction comprising an 110 overflow pipe having a collar integral therewith and provided with a valve seat, the collar having a supporting portion and an enclosing wall, the wall being cut away on the side next to the valve seat, and the supporting portion being cut away to form a shoulder, a bracket having a ring supported on the supporting portion, and a lug engaging against the shoulder and contacting with the cut-away sides of the enclosing wall, a 115 valve stem guided in the bracket, and a valve adapted to be seated in the valve seat and connected with the valve stem.

8. A valve construction comprising an 125 overflow pipe having a collar integral therewith and provided with a valve seat, the collar having walls forming between them a groove, the inner wall being interiorly threaded and the outer wall being cut away on the side next to the valve seat, a bracket 130

having an integral, one-piece, interiorly threaded, continuous ring, a valve stem guide, and an arm connecting the guide and the ring, the ring being mounted in the 5 groove and being supported on the supporting portion, the arm extending through the cut-away side of the wall and engaging against the cut-away sides and having a lug, and the supporting portion having a shoulder engaged by the lug, a pipe having threads engaging with the threads of the collar and the ring, a valve stem guided in the guide, and a valve adapted to be seated 10 on the valve seat and connected with the 15 valve stem.

In testimony whereof, I have hereunto subscribed my name.

JACOB PODOLSKY.
